UNITED STATES PATENT OFFICE.

GEORGE H. WHEARY, OF RACINE, WISCONSIN, ASSIGNOR TO HARTMANN TRUNK COMPANY, A CORPORATION OF WISCONSIN.

CLOTHES-RETAINER.

1,093,222.

Specification of Letters Patent. Patented Apr. 14, 1914.

Application filed July 5, 1911. Serial No. 636,930.

To all whom it may concern:

Be it known that I, GEORGE H. WHEARY, a citizen of the United States, and resident of Racine, in the county of Racine and State of Wisconsin, have invented new and useful Improvements in Clothes-Retainers, of which the following is a description, reference being had to the accompanying drawings, which are a part of this specification.

10 This invention relates to improvements in clothes retainers particularly adapted for use in wardrobe and other trunks.

Trunks of the wardrobe type are usually provided with clothes retainers or followers 15 of rectangular form which are adapted to hold garments, suspended from hangers connected to the upper portion of the compartment, tightly in position to prevent the disarrangement of the garments during the 20 transportation of the trunk. These retainers or followers are held in position by means of straps which are connected to the inner portion of the wardrobe compartment and extend around the garment and 25 the presser bar and have their outer ends adjustably connected together by buckles and considerable time is consumed in adjusting the frame and the straps both in packing and unpacking the trunk. Wardrobe compartments of trunks of the before mentioned 30 type also possess an inherent weakness due to the fact that the full length of the trunk is used for this purpose and medial transversely extending partitions or bracing members for the open side of the compartment would obstruct the opening and interfere with the packing and unpacking of the compartment.

It is one of the objects of the present invention to obviate the before mentioned objectionable features and provide a clothes retainer which may be quickly adjusted in position or removed and when in position will serve to brace the weakest portion of 45 the trunk.

A further object of the invention is to provide a clothes retainer of strong, durable and simple construction and which is inexpensive to manufacture.

50 A further object of the invention is to

provide a clothes retainer which is adapted to brace the sides of the trunk compartment against being crushed inwardly and against bulging outwardly and which may be easily removed from the trunk when it is desired 55 to pack or unpack the trunk.

A further object of the invention is to provide a clothes retainer in which a fixed portion of the retainer serves to reinforce the walls of the wardrobe compartment of 60 the trunk.

With the above, and other objects in view, the invention consists of the improved clothes retainer and its parts and combinations as set forth in the claims, and all 65 equivalents thereof.

In the accompanying drawing in which the same reference characters indicate the same parts in all of the views, Figure 1 is a front view of the upper portion of a trunk, 70 in open position, provided with the improved clothes retainer; Fig. 2 is a sectional view thereof taken on line 2-2 of Fig. 1; Fig. 3 is a vertical sectional view thereof taken on line 3-3 of Fig. 2; Fig. 4 is a detail view, on a larger scale, of the retainer bar locking means; and Fig. 5 is a sectional view taken on line 5-5 of Fig. 4.

Referring to the drawing the numeral 8 indicates the garment compartment of a 80 trunk and 9 the other section hinged thereto. This garment compartment is of ordinary construction and is adapted to be provided in its upper portion with the usual garment hangers (not shown) which support the garments in full length position. A metal guide band or retainer bar engaging member 10 bent to conform approximately to the shape in cross section of three sides of the wardrobe compartment of the trunk is 90 rigidly fastened to the inner walls of said compartment and serves to reinforce said walls. Side portions 11 of said band are spaced a slight distance from the side walls of the compartment and the end portions 95 12 of the band at the forward bends of the spaced portions are of less width than the spaced portions to provide for removing the retainer bar 13 therefrom.

The retainer bar 13 is of sufficient 100

- length to extend from one side of the trunk to the other and is provided with spring actuated bolts 14 which are adapted to enter the rectangular bolt openings 15 and lock said bar in adjusted position. The band engaging ends 16 of the bolts are beveled off at an angle to provide for the bolts automatically snapping into the bolt openings when the retainer bar is pushed inwardly. The casings 17 of the bolts are provided with projecting portions 18 which extend over the spaced portions of the band and also have shoulders 19 formed thereon which extend between the spaced portions of the band and the compartment walls. These projections and shoulders loosely fit over the side edges of the spaced portions of the band and the bar ends bear against the front faces of the band thus securely holding the band sides and the compartment side walls from bulging outwardly or being forced inwardly. The bolts are provided with outwardly extending handles 20 for convenience in releasing the bar from the band.
- 25 In use the garments are suspended in the compartment in the usual way and the retainer bar is then slipped over the ends of the spaced portions of the band and pressed against the garments. In pressing inwardly the spring actuated bolts will snap into the bolt openings and securely and automatically lock the bar in position. The garments will now be securely held in position for transportation without becoming unduly disarranged by the jolts and jars incidental to traveling. When it is desired to remove the garments it is only necessary to withdraw the bolts out of engagement with the band openings and slip the retainer bar off the ends of the spaced portions of the band and the garments may then be removed.
- It is obvious that any number of the bands and retainers may be used in a compartment or that two or more of the retainer bars 45 may be used on the one band if it is desired to space garments apart or to further strengthen the walls of the compartment.
- From the foregoing description it will be seen that the clothes retainer is very simple 50 in construction, easily and quickly adjusted in position and when in the compartment serves the two fold function of holding the garments in position and bracing and reinforcing the walls of the compartment.
- It is to be understood that this invention is not limited to any specified form or arrangement of parts except in so far as such limitations are specified in the claims.
- 60 What I claim as my invention is:
1. A clothes retainer, comprising a bar retaining member having a rear bracing portion with side portions extending at an angle from the opposite ends thereof, said member adapted to be placed within a trunk and to be fastened to the walls of the trunk, and a retainer bar adjustably connected to the side portions of the member.
  2. A clothes retainer, comprising a bar engaging member having a rear portion with side portions extending at an angle from the opposite ends thereof, said member adapted to be placed within a trunk and to be fastened to the three side walls thereof, and a retainer bar adjustably connected to the side portions of the member and having parts which extend around the edges and outer sides of the side portions of the member.
  3. A clothes retainer, comprising a retainer bar provided with locking means on opposite ends, and a U-shaped band adapted and constructed to be positioned within a trunk and fastened to the walls thereof, the stem portions of the U-shaped band being in part spaced from the walls of the trunk and provided with openings which are engaged by the locking means, said retainer bar provided with means engaging and holding the said stem and serving to brace the stems of the U-shaped band against lateral movement toward and away from each other.
  4. A clothes retainer, comprising a retainer bar, casings positioned on opposite end portions of the bar and provided with shouldered projecting portions, spring actuated bolts carried by the casings, and a U-shaped band adapted and constructed to be positioned within a trunk and fastened to the walls thereof, the stem portions of the U-shaped band extending toward the opening of the trunk and being in part spaced from the walls of the trunk and the spaced portions which are automatically engaged by the locking means when the retainer bar is pressed into the trunk and said shouldered projecting portions also engaging the outer side faces of the stem portions, said retainer bar serving to brace the stems of the U-shaped band against lateral movement toward and away from each other.
  5. In combination with a trunk having a garment compartment, of a clothes retainer therefor comprising a U-shaped band positioned within and fastened to the side and rear walls of the garment compartment, the stem portions of the U-shaped band extending toward the opening of the compartment and having portions thereof spaced from the side walls of the compartment and the spaced portions provided with bolt engaging openings, the end portions of said stems being of less width than the spaced portions, a retainer bar, casings positioned on opposite end portions of the bar and provided with shouldered projecting

portions which are adapted to removably extend over the edges and backs of the spaced portions of the band, and spring actuated bolts having beveled band engaging

5 ends which are adapted to slide over the bands and enter the bolt openings when the bar is pressed into the compartment, said bar serving to brace the side walls of the

compartment against lateral movement toward or away from each other.

In testimony whereof, I affix my signature, in presence of two witnesses.

GEORGE H. WHEARY.
